(54) **BRAIDING**

(76) Inventor: **John Thorp**

John Thorpe,
Letters Patent.

The schedule referred to in these Letters Patent and making part of the same containing a description in the words of the said Patent itself of an improvement being a Braiding Machine.

This machine consists of two wheels, the number of which is in proportion to the kind of braid or the number of strands that forms it. These wheels are placed in a circular form, so that the carriers will have a direction pointing to the center where the braid is formed. The inner surfaces of said wheels are concave, forming a curve corresponding with the circle on which they stand, and are of an equal thickness throughout with another, by rays causing them to turn all together, and accurately on their centers, each forming its revolution in a given time.

There are two plates, whose surfaces form the same curve of the said wheels, one of which has a shaft confined to, and revolving from its centre, passing loosely through the centre of the other, thereby fixing it. These plates, when together, constitute what I call a carrier, and is that part of the machine, which contains and carries a spool, bobbin or a clew, and are as many in number as the threads or strands required to form the braid, each of which is placed outside upon the rims of said wheels, and is passed together by a spring, which causes them to pinch the wheels producing a friction ^{insisting} to hold them in their places, and is carried round in their proper route by the wheels so they turn shifting in their circumference from one wheel to another, which is effected by very strong steel. These arms or staves are confined, one to the carrier, and another steadfastly fixed to some permanent part of the frame, with its point extending so near to where the rims of the wheels come in contact as to interfere with the point of the one belonging to the carrier; and their position are such as to cross the said

carriers from the rim of one wheel on to the rim of another; and so on round, from wheel to wheel alternately forming the braid. In the rims of said wheels are notches in which the shafts of the carriers lie, and by which they are retained in their circulation. These notches are so arranged as to come exactly opposite each other, admitting the shaft of the carriers to pass between the wheels as they turn. There are other small notches in said wheels which receive a projection from the carriers, serving also to keep them in their place. This machine is capable of making nearly all kinds of braid, such as whip stings, both single and twilled; also the flat braid, single and twilled, cords &c; and will work from three strands to almost any number; and being constructed to operate without shuttle, receives it subject to no sudden vibration, nor abruptings in its operation; as the strands or threads that form the braid all circulate regularly, without obstruction or impediment of motion, &c.

To convert one of these machines, which is calculated for braiding cords into one that will form a flat braid, no other alteration is necessary than to deprive it of a part of its wheels, letting the carriers return back and forth, instead of continuing round the whole circle. It is however necessary in making flat braid, to have the carriers on one wheel either smaller or larger, so as not to ledge the carriers in the same place from which they were taken. The braid is taken forward by a weight or feeding roller.
